UNITED STATES PATENT OFFICE.

CHRISTOPHER C. SHELBY, OF NEW YORK, N. Y.

CLASP FOR GARMENTS.

SPECIFICATION forming part of Letters Patent No. 298,031, dated May 6, 1884.

Application filed March 12, 1884. (No model.)

To all whom it may concern:

Be it known that I, CHRISTOPHER C. SHELBY, of the city, county, and State of New York, have invented a new and Improved Holder or 5 Clasp for Garment-Supporters; and I do hereby declare the following to be a full, clear, and exact description of the same, reference being had to the accompanying drawings, forming a part of this specification, and to the figures 10 and letters of reference marked thereon.

I will first describe my invention with reference to the accompanying drawings, and will then point out its special features of novelty in the claims at the end of this specification.

15 In the drawings referred to, Figure 1 shows the application of my holder to a stocking-supporter. Fig. 2 is a view of the holder when partially formed; Fig. 3, a view of the same after completion. Fig. 4 is a view of a slightly- 20 modified form of holder.

Similar letters of reference in the several figures indicate like parts.

For convenience of illustration I have shown my holder as applied to a stocking-supporter; 25 but it is obvious that it may be also used to hold up a shirt-sleeve or any other portion of wearer's garments.

The letter A represents the body of the stocking-supporter, and B the holder or clasp. The 30 holder consists of a piece of metal formed with side wings, b b, which are turned over inward, so as to leave a space between them and the back piece and form a longitudinal slot, c, with tapering or flaring mouth c' between the 35 proximate edges of the wings, as clearly shown in Fig. 2. The holder is further provided with an additional wing, d, at its smaller end, which, when turned up against the side wings, b b, assists in holding the latter in position 40 and effectually closes the lower end of the longitudinal slot c. The closure of the lower end

of the slot is of much importance, as it prevents the bight of material caught by the walls of the slot from slipping the entire length of the slot and escaping entirely from the holder. 45 The upper portion of the holder is provided with suitable means for attaching it to the suspending cord or webbing, and these means may consist of two slotted wings, g g, turned down, so as to embrace the cord or webbing, 50 as in Figs. 1 and 2, or of a loop, h, for the insertion of said cord or webbing, as seen in the modification, Fig. 4.

I am aware that prior to my invention a holder for garment-supporters has been made 55 of a piece of sheet metal bent around so as to form a slotted tapering tube open at both ends; and such construction I do not, therefore, lay any claim to; but

What I do claim as my invention is— 60

1. The herein-described garment-holder constructed of tubular tapering form, and having a longitudinal tapering slot closed at the lower or smaller end, as set forth.

2. The holder consisting of the plate provided with the side wings turned so as to form a slotted tapering tube and having also the third wing at the bottom of the slot, for closing the lower or smaller end of the slot and assisting in sustaining the side wings in 70 position, substantially as described.

3. The holder consisting of the plate provided with the side wings turned so as to form a slotted tapering tube, and having the wing at the bottom of the slot, and means for attachment to the cord or webbing, substantially as 75 described.

CHRISTOPHER C. SHELBY.
